United States Patent Office.

PIETRO CINQUINI, OF WEST MERIDEN, ASSIGNOR TO PARKER & WHIPPLE COMPANY.

Design No. 4,677, dated February 28, 1871.

DESIGN FOR A DRAWER-PULL.

The Schedule referred to in these Letters Patent and making part of the same.

I, PIETRO CINQUINI, of West Meriden in the county of New Haven and State of Connecticut, have invented and produced a new and original Design for a Drawer-Pull, of which the following is a specification.

In the accompanying drawing—

Figure 1 is a front elevation of a drawer-pull of my design, and

Figure 2 is a side elevation of the same.

A designates the pull proper, the face B of which is composed of curved and straight lines, and is bordered by a plain ledge, a.

A similar ledge or bar a' is formed a short distance above its lower edge, and parallel to said edge, thus forming two panels upon the face B of the pull A. These panels are interfilled with raised ornamental work.

The upper side and ends of the pull A are ornamented by transverse elevations and depressions b c. Upon each end of the pull A are formed box-like elevations C C, in which are the screw-holes d d.

The faces of the boxes C C are square, and bordered by a ledge, a'', which forms a small panel upon both the upper and lower side of the screw-hole d.

I claim as my invention—

1. The design for a drawer-pull, as shown.
2. The design for the box-like elevation, C C, as shown.

PIETRO CINQUINI.
